UNITED STATES PATENT OFFICE.

LOUIS KEDING, OF MILWAUKEE, WISCONSIN, ASSIGNOR TO JOHN W. SUETTERLE, OF MILWAUKEE, WISCONSIN.

DRAFT CONNECTION.

SPECIFICATION forming part of Letters Patent No. 750,544, dated January 26, 1904.

Application filed May 26, 1902. Serial No. 108,931. (No model.)

To all whom it may concern:

Be it known that I, LOUIS KEDING, a citizen of the United States, residing at Milwaukee, county of Milwaukee, and State of Wisconsin, have invented new and useful Improvements 5 in Draft Connections, of which the following is a specification.

My invention relates to improvements in draft connections adapted especially to be used 10 in connection with fire-engines.

The object of my invention is to provide a form of construction in which the tongue or tongues can be held in raised position preparatory to hitching the horses to the vehicle 15 and when lowered to the position of use securely held in such position, the tongue not being permitted to raise when the speed of the horses is checked.

A further object of my invention is to provide 20 a form of draft apparatus which may be readily disconnected from the vehicle, but which will possess the requisite strength and durability under the heavy strain to which such attachments are subjected in connection 25 with fire-engines.

The device as illustrated in the drawings is adapted for a vehicle intended to be drawn by three horses.

A further object of my invention is to provide 30 means for equalizing the draft in such mechanisms.

In the following description reference is had to the accompanying drawings, in which—

Figure 1 is a top view of the pole mechanism, partly broken away. Fig. 2 is a side view of the same. Fig. 3 is a plan view of the evener-bars, and Fig. 4 is a cross-section drawn on line $\alpha\alpha$ of Fig. 1.

Like parts are identified by the same reference characters throughout the several views.

The tongues 1 are secured to a cross-head 2, which is adapted to be connected with the hounds by means of a bar 3, having a point-bearing 4 at its inner end adapted to engage 45 in a suitable socket in the vehicle in which my invention is applied. 5 represents curved angle-iron braces. These angle-irons 5 are bolted to the respective sides of the bar 3 and are curved outwardly and extended along the

cross-head 2 to its outer ends, being bolted to 50 the cross-head, as shown. By the use of curved angle-irons I not only reinforce the bar 3 and cross-head 2, but also effectually brace the joint between these parts. Near the ends of the cross-head 2 the tongues are 55 attached by means of metallic brackets 6 and bolts 7, the tongues being secured in the brackets by cross-bolts 8, and each bracket being provided with a transverse rest 9, extending underneath the tongue. The under 60 side of each tongue is provided with a latch 10, supported from the tongue by suitable brackets 11 and 12, a spring 13 being used to hold the latch normally in locking position. The under surface of the locking end of the 65 latch is beveled, as shown. 14 is a handle for the manipulation of the latch. With this construction when it is desired to raise either one of the tongues the latch is retracted by backward pressure on the handle 14 to withdraw 70 its locking end from underneath the cross-rest 9, whereupon the tongue can be raised upon the pivot-bolt 8. When it is desired to lower the tongue, the latch will be automatically retracted by the engagement of its beveled 75 surface with the cross-rest 9 until the tongue reaches a horizontal position, when the reaction of the spring 13 will push the latch to locking position underneath said rest.

16 represents brace-rods pivotally secured 80 to the cross-head at 17, and 18 is an aperture in the bar 3 for the reception of the king-bolt 19. At each end of the cross-head 2 I have provided a depending bar 20, which is preferably formed with a rearward pitch and 85 is provided at its lower end with a removable shoe 21, connected with the bar by suitable bolts. These bars 20 and shoes 21 are adapted to support the tongues at their rear ends together with the cross-head when detached 90 from the vehicle. When attached to fire-engines, it is frequently desirable to separate the horses from the engine quickly, this being accomplished by merely withdrawing the king-bolt 19 when the bar 3 draws away from 95 the hounds and drops down slightly until the shoes contact with the ground, whereupon the horses may be driven away with the shoes

sliding on the ground. When the shoe becomes worn out, it may be readily detached from the bar and another substituted therefor.

The evener-bars 25 are secured to the cross-head by pivot-bolts 26, as best indicated in Fig. 2. Each of the evener-bars constitutes a lever, having the inwardly-projecting arm twice the length of that which projects outwardly. The whiffletrees 27 of the two outer horses are attached to the front ends of the levers, while the intermediate whiffletree 28 is connected with the inner or long arms of both levers at 29. As the long arms of the lever are twice the length of the short arms and as the intermediate whiffletree 28 is connected with both of the levers, it is obvious that the draft will be equalized.

I am aware that levers similar to the evener-bars 25 have heretofore been used in connection with an ordinary centrally-pivoted evener-bar, to the outer ends of which the levers were pivotally secured in a manner somewhat similar to the mode of attachment of my bars 25; but so far as I am aware I am the first to provide a form of construction in which such levers are secured to a fixed cross-head or draft-bar, and I attach great importance to the fact that the pivotal supports of the bars 25 are not free to move in the direction of the draft, as they would be if the cross-head were hung upon a central pivot, for by attaching the bars 25 to a substantially rigid support a horse cannot relieve itself of the load by lagging.

In fire-engine houses the horses are usually trained to assume their respective positions in front of the vehicle, and with the described construction the lifting of one of the poles permits the central horse to pass in under the pole to its position between the poles, whereupon the lifted pole can be lowered to a horizontal position, when the latch 10 engages the bracket-rest 9 and prevents the pole from lifting during use. It will of course be understood that the lifted pole is held in its raised position by a suitable support in the barn or engine-house in which the vehicle is located.

Having thus described my invention, what I claim as new, and desire to secure by Letters Patent, is—

1. In a device of the described class, the combination of a cross-head; of a king-bar for connecting the same with the vehicle, provided with a point bearing at its rear end, and having a king-bolt aperture; angle-iron braces reinforcing said bar from the point bearing

to a point near the king-bolt aperture, and curved outwardly and attached to the cross-head; and a plurality of tongues pivotally secured to the cross-head. 60

2. In a device of the described class, the combination with a suitable cross-head; a king-bar for attachment to the vehicle; a plurality of tongues attached to said cross-head by suitable pivot-bolts; brackets projecting from the cross-head and provided with rests for the tongues; and latch-and-catch mechanism located on the tongues and adapted to engage said brackets. 70

3. In a device of the described class, the combination with a suitable cross-head; a king-bar for attachment to the vehicle; a plurality of tongues attached to said cross-head by suitable pivot-bolts; brackets projecting from the cross-head and provided with rests for the tongues; a spring-actuated latch located on the under side of each tongue and adapted to engage underneath the bracket-rest, when the tongue is lowered to horizontal position. 75

4. In a device of the described class, the combination with a suitable cross-head; a king-bar for attachment to the vehicle; a plurality of tongues attached to said cross-head by suitable pivot-bolts; brackets projecting from the cross-head and provided with rests for the tongues; a spring-actuated latch located on the under side of each tongue and adapted to automatically engage underneath the bracket-rest when the tongue is lowered to horizontal position. 80

5. In a device of the described class, the combination with a suitable support, of a tongue pivotally connected therewith; a bracket projecting from the support and provided with a rest for the tongue; and latch-and-catch mechanism located on the tongue and adapted to engage said bracket. 95

6. In a device of the described class, the combination with a suitable support, of a tongue pivotally connected therewith; a bracket projecting from the support and provided with a rest for the tongue; and latch-and-catch mechanism located on the tongue and adapted to engage said bracket; together with a diagonal brace-bar, pivoted to the support and rigidly connected with the tongue. 100

In testimony whereof I affix my signature in the presence of two witnesses.

LOUIS KEDING.
